UNITED STATES PATENT OFFICE.

JOHN M. REED, OF CORVALLIS, MONTANA.

DESK AND CHAIR.

1,334,167.

Specification of Letters Patent. Patented Mar. 16, 1920.

Application filed April 25, 1919. Serial No. 292,690.

To all whom it may concern:

Be it known that I, JOHN M. REED, a citizen of the United States, residing at Corvallis, in the county of Ravalli and State of Montana, have invented certain new and useful Improvements in Desks and Chairs; and I do hereby declare the following to be a full, clear, and exact description of the invention, such as will enable others skilled 5 in the art to which it appertains to make and use the same.

This invention relates to improvements in a desk and chair and has for one of its objects the provision of a device of this character, having a pedestal for supporting the desk and chair.

Another object of this invention is the provision of means whereby the desk may be rotatably and adjustably mounted on the 20 pedestal whereby the angle and the height of the desk may be varied as desired.

A further object of this invention is the provision of means for rotatably and adjustably supporting the chair to the pedestal, whereby the angle and height of the chair with relation to the floor may be varied when desired and also will permit the chair to be folded under the desk in a substantially vertical position.

30 A still further object of this invention is the provision of a desk and chair of the above stated character, which will be simple, durable and efficient, and which may be manufactured and sold at a comparatively low cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a perspective view of a desk and chair constructed in accordance with my invention,

50 Fig. 2 is a perspective view of the desk frame,

Fig. 3 is a vertical sectional view illustrating means for adjusting the desk and chair upon the pedestal,

55 Fig. 4 is a longitudinal sectional view of the desk and chair,

Fig. 5 is a sectional view taken on the line 5-5 of Fig. 3, illustrating the means for holding the various parts in adjusted position.

Referring in detail to the drawings, the numeral 1 indicates as an entirety, a pedestal consisting of a base 2, which is folded or otherwise secured to the flooring as shown at 3.

The pedestal 1 has a cylindrical portion 4, which is internally and externally screw-threaded as illustrated in Fig. 3. A supporting rod 5 of cylindrical formation has its lower end externally threaded and threaded into the cylindrical portion 4 of the pedestal and has its upper end apertured to receive a set screw 6 for holding a cylindrical collar 7 therein at various adjusted positions. A plate 8 is formed upon the 75 upper end of the collar 7 and is secured to the bottom of a desk 9. The plate 8 is provided with an annular groove 10 about the collar 7 to receive the upper end of the cylindrical supporting member 5.

A housing 11 is internally screwthreaded at its lower end and threaded upon the cylindrical portion 4 of the pedestal 1 and has its upper end apertured to receive a set screw 12 for holding the cylindrical supporting member 5 in various adjusted positions in the pedestal 1.

The housing 11 is provided with an annular groove 13, which is surrounded by a collar 14 having an inwardly directed flange 15, which is received within the groove 13 for rotatably supporting the collar 14 upon the housing 11. The collar 14 has formed thereon, oppositely disposed arms 16, which have their outer ends bent in substantially U-shaped formation as shown at 17.

A pair of relatively spaced arms 18 are pivoted to the free ends of the substantially U-shaped portion 17 as shown at 19 and have their inner ends normally in engagement 100 with the under faces of the arms 16 for supporting them in a substantially horizontal position. The arms 18 have secured thereon, a seat 20. A set screw 21 is carried by the collar 14 and is adapted to be threaded 105 in engagement with the housing 11 to prevent the rotation of the arms 16 about a vertical axis.

A pair of substantially L-shaped members 22 are connected by transverse members 23 and bracing strips 24. The bracing strips 24 are also connected to horizontal

braces 25, which are in turn connected to the vertical arm portions of the substantially L-shaped members 22. A back rest 26 is secured to the vertical arm portions of the substantially U-shaped members 22 for co-operating with the seat 20 in forming a chair. The back rest 26 extends upwardly and closes the front wall to the desk 9. The desk 9 consists of a top 27 and side walls 10 28, which are secured to the sides of the substantially L-shaped members 22 and to the horizontal braces 25. The desk 9 has its rear wall open so that articles may be placed within the desk upon the bottom thereof 15 when desired.

In operation, when it is desired to adjust the height of the desk 9 with respect to the floor, the collar 7 may be adjusted within the cylindrical supporting member 5 by releasing the set screw 6. The desk may be further adjusted in height from the floor by rotating the cylindrical member 5 within the cylindrical portion 4 of the pedestal 1 by releasing the set screw 12. The desk 9 25 also may be adjusted at various angles with relation to the base by releasing the set screw 12.

The seat 20 may be readily folded up in engagement with the back rest when desired 30 by swinging the arms 18 upon their pivots 19. When it is desired to remove the seat 20 from in front of the back rest 26, the set screw 21 may be released from engagement with the housing 11, permitting the collar 35 14 to rotate thereon, swinging the seat under

the desk as illustrated in dotted lines in Fig. 1.

While I have shown and described the preferred embodiment of my invention, it will be understood that minor changes in 40 construction, combination and arrangement of parts may be made without departing from the spirit and scope of the invention as claimed.

Having thus described my invention, 45 what I claim is:

1. A desk and chair comprising a pedestal, a desk carried by said pedestal, a back rest carried by said desk, a housing threaded to said pedestal, a collar rotatably mounted 50 on said housing, oppositely disposed arms formed upon said collar, and a seat pivotally connected to said arms.

2. A desk and chair comprising a pedestal, a desk rotatably and adjustably secured to 55 said pedestal, a back rest carried by said desk, a collar rotatably mounted upon said pedestal, oppositely disposed arms formed on the collar and having their free ends bent in substantially U-shaped formation, arms 60 pivoted to the ends of the substantially U-shaped ends of the first named arms, and a seat carried by the last named arms.

In testimony whereof I affix my signature in presence of two witnesses.

JOHN M. REED.
